LIFE RAFT RELEASE

Justin D. Petouhoff, New York, N. Y.

Application April 24, 1943, Serial No. 484,452

2 Claims. (Cl. 9—33)

1

My invention relates to life raft release and has particular reference to device for supporting life rafts on ships and for manually or automatically releasing the rafts from the ship when needed.

My invention has for its object to provide means to support a life raft on board of a ship in such a way that the raft can be easily and quickly released and allowed to drop into the water when the ship is in danger of sinking.

Another object of my invention is to provide means to automatically release the raft when the ship is already sinking, the release being accomplished by the pressure of water from underneath. I provide for this purpose a float releasably supported on the ship near the raft and adapted to be raised by its buoyancy when the ship is sinking, the buoyancy being sufficient to release the raft from the ship.

My invention is more fully described in the accompanying specification and drawings in which:

Fig. 1 is a sectional elevational view of my raft and its supporting means on board of a ship;

Fig. 2 is a front view of the same;

Fig. 3 is a top plan view of the same;

Fig. 4 is an end view of a life boat with my automatic releasing device.

My life raft release consists of brackets 1 attached to the side 2 of a ship 3 for supporting a life raft 4. The raft is held by ropes 5 passing through cleats 6 having concave sides for engaging the raft, the outer ends of the ropes being fastened to the brackets 1, the inner ends being attached to a plate 7. The plate has a hole at the end for engaging a hook 8 pivotally supported at 9 on a post 10 which may be made of angle iron supported on the deck 11 of the ship. The hook in its operative position, as shown in Fig. 1 pulls on the ropes 5 thereby pressing the life raft by the cleats to the side of the ship. The hook is retained in this position by a lever 12 having a hole for the hook 8. The lever is pivoted at 13 on the post 10 and has a handle 14 for its manual rotation and release from the hook 8. A pin 15 may be used for locking the lever in the operative position, the pin engaging a corresponding hole 16 in the end of the hook 8.

For releasing the raft the lever is turned by the handle into an inoperative position as shown in dotted lines in Fig. 1. The hook, when released, is turned downward by the pull of the ropes 5 thereby allowing the plate 7 to slide off the hook. The weight of the raft will cause the

2

ropes 5 to swing away from the ship, the raft falling into the sea.

For automatically releasing the raft when the ship is already sinking, a float 17 is provided, 5 supported in a cage 18 attached to the post 10. The float rests on the bottom of the cage, the latter being open at the top so that the float can be raised by the pressure of water underneath when the ship is sinking. The float can 10 be formed of a number of hollow containers connected together at 19. A cable or rope 20 is attached to the float, the other end of the cable being attached at 21 to a lever 22. The buoyancy of the float, when submerged in water, is such 15 that it will lift the lever 22 against frictional resistance of the moving parts. The lever 22 is provided with a gear sector 23 engaging a similar sector 24 on the lever 12 so that the lever 22, when raised, will rotate the lever 12, releasing 20 the hook 8 and freeing the raft.

A similar device is provided for a life boat 25 as shown in Fig. 4. The boat rests on block 26 on the deck 11 and is held down by bars 27. One end of each bar is fastened by ropes or lashes 25 to hooks 29 on the deck 11. The other end of the bar has an extension 30 with a pivot 31 at the lower end for a hook 32. The latter is held under tension by ropes or lashes 33 fastened to a hook 34 on the deck 11. The end of the hook engages an arm 38 pivoted at 35 to the end of the bar 27 and having a handle 36 at the middle and a float 37 at the end. The hook 32 can be released manually by lifting the arm 38 by the handle 36 or it can be released automatically when the float 37 is submerged in water.

It is understood that my life raft release may be further modified without departing from the spirit of the invention, as set forth in the appended claims.

40 I claim as my invention:

1. Life raft release comprising means to releasably support a life raft at the side of a ship; a cord attached at the outer end to the raft supporting means and engaging the raft, the inner end of the cord extending onto the upper deck of the ship; a plate with a hole at the inner end of the cord; a hook pivotally supported at its upper end on the deck, the middle portion of the hook being engaged by the plate, the lower portion of the hook extending substantially horizontally away from the raft; a lever rotatively supported at the upper end on the deck, the lower end of the lever slidably engaging the end of the hook thereby retaining the hook in its horizontal operative position, the upper end of the lever

having a gear sector; a handle on the lever for its manual operation; a second lever pivotally supported at the middle, one end of the second lever having a gear sector engaging the gear sector of the first lever; and a float connected to the free end of the second lever for rotating the second lever thereby rotating the first lever and releasing the hook and the raft supporting cord.

2. Life raft release comprising means to releasably support a life raft at the side of a ship; a cord attached at the outer end to the raft supporting means and engaging the raft, the inner end of the cord extending onto the upper deck of the ship; a plate with a hole at the inner end of the cord; a hook pivotally supported at its upper end on the deck having a short portion ver-

tically extending downwards from the pivot engaged by the plate, and a long portion extending substantially horizontal away from the raft; a substantially vertical lever rotating support at the upper end and having a handle at the lower end, the lever having an opening engaging the horizontal portion of the hook, thereby preventing the hook to be turned over by the pull of the cord; a gear sector at the upper end of the lever; a second lever pivotally supported at its middle portion; a gear sector at one end of the second lever in mesh with a gear sector at the end of the first lever; and a float connected at the other end of the second lever.

JUSTIN D. PETOUHOFF.
